UNITED STATES PATENT OFFICE

162,909

MANURE SPREADER OR SIMILAR ARTICLE

George W. Walker, Detroit, Mich., assignor to
Dearborn Motors Corporation, Highland Park,
Mich., a corporation of Delaware

Application February 17, 1949, Serial No. 920

Term of patent 3½ years

(Cl. D14—3)

To all whom it may concern:

Be it known that I, George W. Walker, a citizen of the United States, and a resident of the city of Detroit in the county of Wayne and State of Michigan, have invented a new, original, and ornamental Design for a Manure Spreader or Similar Article, of which the following is a specification, reference being had to the accompanying drawing, forming a part thereof.

On the drawing:

Figure 1 is a front side perspective view of a manure spreader, embodying this invention;

Figure 2 is a rear side perspective view of the manure spreader, and

Fig. 3 is a plan view of the manure spreader.

The characteristic features of my design reside in the portions shown in full lines in the drawing.

I claim:

The ornamental design for a manure spreader, or similar article, as shown and described.

GEORGE W. WALKER.
